UNITED STATES PATENT OFFICE.

GEORGE TAINTER, OF WATERTOWN, MASSACHUSETTS.

IMPROVEMENT IN VENTILATING-DAMPERS.

Specification forming part of Letters Patent No. 35,269, dated May 13, 1862.

To all whom it may concern:

Be it known that I, GEORGE TAINTER, of Watertown, in the county of Middlesex and State of Massachusetts, have invented a new and Improved Ventilating-Damper for Stoves and Furnaces; and I do hereby declare that the following is a full, clear, and exact description of the same, reference being had to the accompanying drawings, making a part of this specification, in which—

Figure 1 is a vertical central section of my invention, taken in the line $x x$, Fig. 2. Fig. 2 is a horizontal section of the same, taken in the line $y y$, Fig. 1.

Similar letters of reference indicate corresponding parts in the two figures.

This invention consists in the employment or use of a hinged conical damper and ventilating-register constructed and applied to the flue or pipe of a stove or furnace in such a manner that the damper will be opened and closed or adjusted simultaneously with the adjustment of the register and a superior ventilating attachment attained.

To enable those skilled in the art to fully understand and construct my invention, I will proceed to describe it.

A represents the pipe or flue of a stove or furnace, and B is a band which encompasses it and is allowed to turn freely thereon. This band B has two or more openings, a , made in it, and similar openings, b , are made in the part of the pipe or flue which is covered by the band. The band B forms a register, by turning which more or less air may be admitted into the pipe or flue A, or the flue cut entirely off from the external air when desired.

C is a hollow circular damper formed of two equal vertical parts, $c c$, which are connected at their lower ends by joints $d d$. This damper when closed has a small circular opening, d' , at its top, as shown in both figures. The damper C is connected with the band or reg-

ister B by means of a rod, D, which passes through oblong circumferential slots e in the flue A and through the slots f in the two parts $c c$ of the damper, the ends of said rod being secured in the band, as shown clearly in Fig. 2.

The relative position of the rod D and slots f of the damper with the openings $a b$ of the band B and flue A is such that when the openings $a b$ are in line with each other the damper C will be closed, and when the damper is open the opening b of the flue A will be closed or covered by the band B. The two parts $c c$ of the damper are adjusted by the movement of the band B, the rod D forming the connection between the two.

From the above description, therefore, it will be seen that as the external air is admitted into the flue A the draft of the stove will be proportionally checked and the draft increased as the openings b are closed. By this arrangement a room may be ventilated in the most expeditious and perfect manner.

The damper is shown in an open state by the red lines, and it will be understood that when the damper is closed the small opening d' at its top will admit of the escape of gases up into the flue A.

I do not claim the admitting of external air into the pipe or flue of a stove, for that has been previously done for the purpose of ventilating apartments; but

I do claim as new and desire to secure by Letters Patent—

The combination of the conical damper C and band or ventilating-register B, connected together and applied to the flue or pipe for joint operation, substantially as and for the purpose specified.

GEORGE TAINTER.
